UNITED STATES PATENT OFFICE

ARTHUR F. ROSWURM, OF LAKEWOOD, OHIO

SOCKET

Application filed January 31, 1931. Serial No. 512,692.

This invention relates to an electric socket adapted particularly for use on such electric appliances as flatirons, toasters or any other such appliance provided with a pair of posts upon which such socket is adapted to be received.

In devices of this type considerable difficulty has been experienced because of the tendency of the conductors making up the cable to break under the strain when the socket is detached from the appliance by pull on such cable. The reason for this difficulty is that the construction is usually such that cables themselves must transmit the force of the pull to the contact members which are usually in frictional engagement with the posts of the applicant when the socket is in position thereon.

The principal object of my invention is to provide a socket of very simple construction which will overcome these difficulties by an arrangement causing the force of the pull on the cable to exert not only a separating force between the socket shell and the posts of the appliance, but also to exert a considerable pull in a direction lateral to the extent of such posts.

I attain the foregoing and other and more specific objects in and through the construction hereinafter described and illustrated in the accompanying drawing in which Fig. 1 is a partial sectional view showing the device in position on an electric flatiron; Fig. 2 is an exaggerated showing of the change in position of the contact members when the socket is removed from the appliance; and Fig. 3 is a sectional view on the line 3-3 of Fig. 1.

In the drawing, the numeral 10 indicates a flatiron of any desired construction provided with spaced terminal posts 11 upon which the socket embodying my invention is to be received. In the embodiment of my invention illustrated, I provide a pair of shell portions 12 and 13 made of hard rubber, bakelite or similar insulating material. These shell portions will be hollowed out centrally and provided with a rim extending around the edge, as best seen in Fig. 3, the rims of the two shell portions abutting to

define a hollow shell. A small opening is left at one end for the reception of an annular bushing 14 through which a cable 15 is adapted to extend.

Centrally of one of the shell members 13, I provide a rib 16 of a height to reach substantially to the other shell member when the two are juxtaposed to form a complete shell. This rib will preferably be somewhat wedge shaped as indicated in the drawing. Near the wider end of the rib, I provide a pair of L-shaped grooves 17 which receive an angular or hooked portion of spring members 18. Each of the spring members 18 includes a hooked portion adapted to fit into the grooves 17 and a somewhat curved contact portion 19 as well as a sharply outwardly curved terminal portion 18^a.

Attached to each of the terminal portions 18^a is one of the conductors 20 which make up the cable 15. The attachment of the cable 20 to the portion 18^a may be effected in numerous ways such as the provision of a terminal notch and an opening through which the end of the conductor extends and is knotted as shown at 21, or by means of binding posts or solder as preferred. The two halves of the shell may be secured together by a plurality of bolts 23 extending therethrough. These preferably extend through the rib 16.

With the foregoing in mind, it will be obvious that a pull on the cable 15 will result not only in the exertion of the force intended to pull the socket off the plugs 11 but also in a component at substantially right angles to the direction of the plugs 11 tending to move the contacting portion 19 of the spring members 18 laterally with respect to such posts. The annular bushing 14 will of course have an opening of sufficient size to allow a slight sliding motion of the cable 15 or the conductors 20 constituting it.

From the foregoing, it will be obvious that I have provided a device well adapted for its intended purpose and exceedingly simple in construction and while I have shown and described the preferred embodiment of my invention, I wish it understood that numerous changes may be made without departing from

the scope of my invention as defined in the appended claims.

Having thus described my invention, what I claim is:—

1. An electric socket including a shell made in part at least of insulating material, an opening to the interior of said shell adapted to receive a post, a contact in said shell adapted to engage said post, means adapted to resiliently urge said contact into engagement with said post, a conductor entering said shell and electrically connected with said contact, and means including portions of the recited structures whereby a pull on said cable exerts a force on said contact a considerable component of which tends to move said contact in a direction lateral to said post.
2. An electric socket including, a pair of shell members made of insulating material, a central, longitudinally extended rib integral with one of said shell members, a pair of L-grooves formed in said rib near one end of said shell, each being substantially as deep as the thickness of said rib, a narrow opening at the other end of said shell, a pair of spring members, each having a hook-shaped end portion received in one of said L-grooves, an outwardly bowed central contact portion and a sharply outwardly bent terminal portion, a pair of conductors passing through said narrow opening and connected one to each said terminal portion.
3. An electric socket including, a pair of shell members made of insulating material, a central, longitudinally extending rib integral with one of said shell members, a pair of L-grooves formed in said rib near one end of said shell, each being substantially as deep as the thickness of said rib, a narrow opening at the other end of said shell, a pair of spring members, each having a hook-shaped end portion received in one of said L-grooves, an outwardly bowed central contact portion and a sharply outwardly bent terminal portion, a pair of conductors passing through said narrow opening and connected one to each said terminal portion, said rib extending substantially the full length of said spring member.
4. An electric socket including, a pair of shell members made of insulating material, a longitudinally extending rib intergral with one of said shell members, a pair of L-grooves formed in said rib near one end of said shell, a narrow opening at the other end of said shell, a pair of spring members, each having a portion received in one of said L-grooves, an outwardly bowed central contact portion and an outwardly bent terminal portion, a pair of conductors passing through said narrow opening and connected one to each said terminal portion.

In testimony whereof, I hereunto affix my signature.

ARTHUR F. ROSWURM.
